UNITED STATES PATENT OFFICE.

FREDERICK RICHMAN STEVENSON, OF MITCHAM, SOUTH AUSTRALIA, AUSTRALIA.

SPRING CONSTRUCTION.

Application filed April 5, 1922. Serial No. 549,819.

To all whom it may concern:

Be it known that FREDERICK RICHMAN STEVENSON, a subject of the King of Great Britain, residing at Princes Road, Mitcham, in the State of South Australia, Commonwealth of Australia, hath invented certain new and useful Improvements in and Connected with Spring Construction, of which the following is a specification.

10 My invention relates to improvements in and connected with spring cushions for vehicles and upholstery, the object of the same being to construct a spring cushion in such a manner as to afford very great resiliency without rendering it liable to work out of shape, this object being achieved by the application and use of various elements constituting a new constructional combination the parts of which are so arranged as 20 to produce the desired effect.

The invention herein described is intended to include the upholstery for the backs of railway carriages and the beds of sleeping cars, sofas, and analogous structures.

25 The cushion constructed in accordance with my invention may be built upon either a wire, iron, or wooden foundation, a corresponding shape of wire being used to control the shape of its upper edge, a special 30 feature of construction consisting of an intermediate frame of wire of smaller dimensions which is attached by suitable means to vertically arranged outer rows of coil springs which are connected both to the 35 top and bottom frame.

These springs are held in position by suitable means and are tied to each other in adjacent groups by wire ties which are joined up so as to afford great stability to the structure which is further strengthened 40 by hinged diagonal stays crossing from the top frame to the intermediate frame. The loose ends of intermediate groups of stays may also be joined together with wire attachments if necessary but in the majority of cases this will not be required, but in order that my invention may be clearly understood I will further describe the same 45 by aid of the accompanying illustrative drawings wherein:—

Fig. 1 is a plan of a cushion showing methods of attachment, the bottom attachments and cross frame wires being omitted in portion of the illustration.

50 Fig. 2 is a longitudinal or side elevation of the cushion.

Fig. 3 is an outlined end view of the structure showing cross stays and middle connecting plates.

Fig. 4 is an inverted view of portion of 60 the structure showing bottom attachment plates.

Fig. 5 is an inverted view of a single spring showing bottom attachment plate on 65 a larger scale.

Fig. 6 is an end view of cushion showing a foundation frame of wood.

Fig. 7 is an attachment device constructed of wire for intermediate springs.

Figures 8 and 9 are a plan view and side 70 elevation, respectively, of an attachment device for half coil springs.

In each of the illustrations similar letters of reference are used to denote similar or corresponding parts wherever they occur. 75

In the drawings *a* is the foundation frame of steel, wire, wood, or other material upon which the longitudinal and lateral cross-wires *b* are stretched. To these cross-wires I attach the coil springs *c* by means of any 80 convenient fastening device such for instance as the fastening shown at *d* which consists of two strips of metal slotted at their ends for the clearance of the cross-wires, the wings of the slotted portions being bent round the outer coil of the spring as indicated in Fig. 5, the strips of metal which constitute the fastening device being centrally punched out as indicated, one strip 85 having a clean hole punched through the metal whilst the other strip has triangular shaped or other lapping pieces left in the openings which are subsequently bent over to bind the two strips together as will be readily understood on reference being made 90 to Fig. 5 of the drawings.

The fastening device above referred to is adaptable to double ended springs of the nature more particularly shown in Figs. 2 and 3 of the drawings, and also used in 100 part of Fig. 6, but it is desirable that in the outer row of springs in Fig. 6 a spiral spring of the type commercially known as half-coil springs should be applied having its lower end of relatively small diameter 105 as shown at *c'* in that figure, in which case the fastening device may be of the nature shown in Figs. 8 and 9 and consists of a somewhat cone shaped split thimble adapted at its lower ends for the reception of cross-wires, its upper ends being flanged outwardly to engage the small coil of the spring 110

as indicated. These fasteners may have the extremity of one if its sides or wings cut away as indicated in Fig. 8 of the drawings.

In the upper portion of the cushion I provide a steel wire frame *f* which may be similar in size and shape to the wire frame *a*, and to this upper frame the outer rows of springs are attached by a simple form of attachment such as *g* but the cross-wires 10 are dispensed with in the upper frame except that parallel with the outer edge of the upper frame I supply a single frame wire *j* which is also engaged by the outer row of springs by means of attachment 15 plates. I find in actual practice that it is advantageous to leave the intermediate rows of springs loose or unattached at their top ends.

A very important feature of my invention 20 consists of the construction and the arrangement of an intermediate frame *k* which is usually situated midway between the upper and lower frame and is of smaller size than the former as more clearly indicated 25 in Figs. 1 and 6 of the drawings as well as in other figures.

The coil springs are fastened to each other opposite to this frame by means of a suitable fastening device consisting preferably of 30 a disc *l* having holes *m* formed therein from whence the attachment wires *n* radiate and terminate with bent or hooked ends as clearly indicated in Fig. 3 of the drawings.

In some cases a simpler fastening structure can be used consisting of a wire loop *o* which may be pressed into the form of a cross as indicated in Fig. 7, the ends being turned downwardly and inwardly so 40 as to make a hook suitable for gripping over the wires. Either this device or simple wire hooks can be used if it is desired

to join the intermediate springs together, the wire attachments being either diagonally arranged as illustrated or they may 45 be at right angles to the frame.

For the further purpose of strengthening my cushion I use diagonal stays *p* preferably consisting of wire similar to that which is used for constructing the frame. 50 These wires extend across the cushion from the top frame bars to the bars of the intermediate and may be repeated in the bottom of or across the structure and are preferably capable of rotation where joined 55 to the frame to allow for the relative movement of the frame bars when the springs are compressed.

Having now particularly described my said invention and in what manner the 60 same is to be performed I declare that what I claim is:—

In improvements in and connected with spring cushions for vehicles and upholstery wherein cross-wires are used for supporting 65 springs, means for attaching said springs to the cross-wires consisting of two strips of metal placed at right angles to each other, one of which said strips is punched with a square hole, the other being punched in such 70 a manner as to form lapping pieces which are passed through the holes of the former and bent over to bind the two strips together, the ends of the strips being slotted for the clearance for the cross-wires and the 75 wings of the slotted portions being bent round the outer coil of the spring.

In testimony whereof he hath affixed his signature in presence of two witnesses.

FREDERICK RICHMAN STEVENSON.
